DESIGN FOR A SWIM SUIT OR SIMILAR ARTICLE

Margit Fellegi Laszlo, Los Angeles, Calif., assignor to Cole of California Inc., Los Angeles, Calif.

Application December 4, 1944, Serial No. 116,689

Term of patent 7 years

(Cl. D3—17)

To all whom it may concern:

Be it known that I, Margit Fellegi Laszlo, a citizen of the United States of America, residing at Los Angeles, in the county of Los Angeles and State of California, have invented a new, original, and ornamental Design for a Swim Suit or Similar Article, of which the following is a specification, reference being had to the accompanying drawing, forming a part thereof.

The figures in the drawing are:

I claim:

The ornamental design for a swim suit or similar article, as shown and described.

MARGIT FELLEGI LASZLO.
